DESIGN FOR A DOLL OR THE LIKE

Gladys W. Ainge, Bryn Mawr, Pa.

Application August 5, 1944, Serial No. 114,753

Term of patent 14 years

(Cl. D34—4)

To all whom it may concern:

Be it known that I, Gladys W. Ainge, a citizen of the United States and a resident of Bryn Mawr, in the county of Montgomery and State of Pennsylvania, have invented a new, original, and ornamental Design for a Doll or the like, of which the following is a specification, reference being had to the accompanying drawing, forming a part thereof.

In the drawing, Fig. 1 is a front view; Fig. 2 is a side view and Fig. 3 is a back view on a reduced scale of a doll showing my new design.

I claim:

The ornamental design for a doll or the like, as shown.

GLADYS W. AINGE.
